THE NATIONAL LITHOGRAPHING COMPANY,
WASHINGTON, D. C.

UNITED STATES PATENT OFFICE.

GODFRIED LAUBE, OF HURON, SOUTH DAKOTA, ASSIGNOR OF ONE-HALF TO
JOSEPH HYMANS, OF CHICAGO, ILLINOIS.

CHURN.

SPECIFICATION forming part of Letters Patent No. 514,859, dated February 13, 1894.

Application filed August 10, 1893. Serial No. 482,838. (No model.)

To all whom it may concern:

Be it known that I, GODFRIED LAUBE, a citizen of the United States of America, residing at Huron, in the county of Beadle and State of 5 South Dakota, have invented certain new and useful Improvements in Churns, of which the following is a specification, reference being had to the accompanying drawings.

This invention relates to certain new and 10 useful improvements in churns and particularly to that class known as rocking or swinging churns.

The object of the invention is to so construct a churn that different swings or motions may be acquired by simple adjustments of the hangers on their supports; furthermore to so arrange the parts that the power required in oscillation will remain at the minimum throughout the operation, and to 15 combine in a churn a simple construction with efficient service and inexpensive manufacture.

With these and other objects in view the improvement consists in various novel details 20 of construction, arrangement and combinations of parts to be hereinafter more fully described and specifically pointed out in the claim.

In describing the invention in detail, reference is had to the accompanying drawings forming part of this specification and wherein 25 like figures of reference indicate corresponding parts in the several views, in which—

Figure 1. is a view in side elevation showing in dotted lines the throw effected when hangers are in position near the center of the support. Fig. 2. is a view in side elevation showing in dotted lines the throw effected when adjusted at the ends, and Fig. 3. is an 30 end view of the machine. Fig. 4 is a view of the dasher.

In the drawings,—1, indicates the vessel or body of the churn proper in which the cream is agitated, which may be made square, cylindrical or in any of the well known shapes; 35 2, the opening at the top of the receptacle and 3, the cover for said opening, which may be retained in position by means of the friction of the flanges against the side of the opening 40 or other suitable means. The handles 4, by which motion is given the vessel, are attached at any convenient part thereof, a one side and one end handle being preferred.

The body of the churn is pivoted as at 8, 8, to suitable hinges 9, 9, having their free ends 55 engaged by notches 10, 10, a series of which is arranged in the cross pieces 11, held in position by frame work consisting of the corner posts 12, 12, 12, 12, suitably braced to withstand the strain incident to the use of the 60 churn. Interiorly a dasher 6, provided with slots is arranged diagonally of the flow of the cream when in motion, and as the agitation is thereby increased the more efficient separation of the oily globules from the other portions is induced. The cleats 8, 8, between which the dasher is arranged, at the bottom 65 serve to retain it in its normal position while in use, while at the top the said dasher is held in position in the angles formed by the walls 70 of the opening 2.

Particular attention is called to the different motions which can result from the adjustment of the hangers in the notches of the cross pieces. For instance, when the hangers are adjusted in the extreme end notches of the cross pieces, the body will be given a tilted motion, as shown in dotted lines, Fig. 2. While if moved one or two notches toward the center, a horizontal motion will be 75 imparted and if placed still nearer the center, a dipping or curved motion would be produced as shown by dotted lines, Fig. 1. It will be readily understood that this principle could be applied to washing machines with 80 satisfactory results; also that various changes may be made in the detail construction without departing from the general idea involved.

Having fully described my invention, what 90 I claim as new, and desire to secure by Letters Patent, is—

In a churn, the combination with the body portion provided with a dasher, of the hangers supporting the body portion and the 95 notched cross pieces of the carrying frame in which the hangers are adjustably secured whereby the swing of the body portion may be varied, substantially as described.

In testimony whereof I affix my signature in 100 presence of two witnesses.

GODFRIED LAUBE.
